UNITED STATES PATENT OFFICE.

GEORGE BONENBERGER, OF EVANSVILLE, INDIANA, ASSIGNOR TO STEEL SCAFFOLDING COMPANY, OF EVANSVILLE, INDIANA, A CORPORATION OF INDIANA.

SHINGLING-BRACKET.

1,109,506.

Specification of Letters Patent. Patented Sept. 1, 1914.

Application filed February 12, 1913, Serial No. 747,944. Renewed April 6, 1914. Serial No. 830,087.

To all whom it may concern:

Be it known that I, GEORGE BONENBERGER, a citizen of the United States, residing at Evansville, county of Vanderburgh, and 5 State of Indiana, have invented certain new and useful Improvements in Shingling-Brackets, of which the following is a specification.

This invention relates to shingling brackets.

10 My object is to provide a simple, inexpensive, strong and durable shingling bracket which can be quickly and easily applied to shingles or placed on the roof and utilized 15 in connection with a piece of timber, as a support for the shingler.

20 My object particularly is to provide in a shingling bracket an improved claw or prong combined with the bracket in such manner 25 that when the piece of timber is applied thereto, the timber will be held against detachment and the weight of the shingler on the piece of timber will tend to very firmly 30 secure the bracket in position on shingles already placed on the roof, two or more of 35 the brackets being used in connection with a single piece of timber in actual practice.

The invention is fully set forth herein- 40 after and the novel features are recited in 45 the appended claim.

In the accompanying drawings: Figure 1 50 is a perspective view showing how the invention is used; and Fig. 2, a detail perspective of the shingling bracket.

55 The bracket has a metallic base 1 which at one end is provided with a more or less flattened part 2 having a beveled edge 3 to permit it to be readily inserted under the lower end of the uppermost shingle. The 60 other end of the base has downwardly turned prongs or teeth 4 constituting a claw adapted to enter another shingle.

65 Riveted or suitably secured at 5 to the base 1 is a hook 6 which overhangs the flattened part 2 and is adapted to overlap the piece of timber 7 used when the bracket is applied to a roof, as shown in Fig. 1, from 70 which it will appear that two or more of the brackets are used to hold opposite ends of 75 the piece of timber.

Pivoted at 8 to the hook 6 is a claw abutment 9 having teeth or prongs 10. This claw abutment, as shown in Fig. 1, is of such length that it is adapted to engage the lower part of the uppermost shingle and to 55 be forced thereinto by the pressure exerted against it by the piece of timber 7, the arrangement being such that the weight of the shingler on the piece of timber tends to press the teeth of the claw abutment into the 60 shingle and also the teeth 4 into another shingle. The weight of the shingler on the timber 7 also causes the shingle to be firmly clamped between the base and the claw abutment, all of which will be apparent 65 from Fig. 1.

Having inserted the part 2 of two or more of the brackets underneath the uppermost row of shingles, the piece of timber 7 is inserted under the hooks and against the 70 claw abutment. The shingler then rests upon the piece of timber while nailing other shingles on the roof. From time to time, the piece of timber is removed, the claw abutments knocked out of engagement with 75 the shingles and the shingling brackets brought to a higher point on the roof.

Having thus described my invention, what I claim as new and desire to secure by Letters Patent, is:

80 A shingling bracket embodying a base having means adapted to engage a shingle, a hook secured to the base and arranged in overhanging relation thereto in position to embrace a piece of timber, and an abutment 85 pivoted to the bill of the hook intermediate the ends of the latter with its free end extending toward the free end of the hook in abruptly inclined or angular relation to the hook and base and in position to be 90 pressed by the timber into engagement with a shingle.

In testimony whereof, I hereunto affix my signature in presence of two witnesses.

GEORGE BONENBERGER.
